CLAIM

The ornamental design for an elevator sill, as shown and described.

DESCRIPTION

FIG. 1 is a perspective view of the elevator sill of the present invention;

FIG. 2 is an enlarged front view thereof;

FIG. 3 is an enlarged rear view thereof;

FIG. 4 is a right side view thereof;

FIG. 5 is a left side view thereof;

FIG. 6 is a bottom view thereof; and,

FIG. 7 is a top view thereof.

The elevator sill has been broken in the center for ease of illustration.
